DESIGN FOR A RING

Oren P. Burch, Aberdeen, Wash.

Application February 5, 1945, Serial No. 117,777

Term of patent 7 years

(Cl. D45—10)

To all whom it may concern:

Be it known that I, Oren P. Burch, a citizen of the United States, residing at Aberdeen, Grays Harbor County, Washington, have invented a new, original, and ornamental Design for Rings, of which the following is a specification, reference being had to the accompanying drawing, forming part thereof, wherein—

Fig. 1 is a top view of the ring embodying my design.

Fig. 2 is a side view of the same.

Fig. 3 is an edge view taken from the left of Fig. 1.

Fig. 4 is an edge view of the ring taken from the right of Fig. 1.

I claim:

The ornamental design for a ring, as shown and described.

OREN P. BURCH.
